SWITCH DEVICE FOR ELECTRIC DRILLS

Frank B. Hamerly, Aurora, Ill., assignor to Independent Pneumatic Tool Co., Chicago, Ill., a corporation of Delaware

Application October 18, 1935, Serial No. 45,544

6 Claims. (Cl. 172—36)

This invention relates to relatively small portable electric hand drills of the gun or pistol type.

The drill is held in and supported by one hand grasping the body of the drill on opposite sides 5 and the single handle at the rear end of the drill. The handle is of the pistol grip type and is preferably made hollow to provide an air duct for the cooling system for the motor and to accommodate one of the brushes of the motor and the 10 connector by which said brush is electrically connected to one of the electric supply wires for the drill.

The motor is of the horseshoe type thereby disposing the field coil of the motor above its armature and thus providing space in the drill casing 15 above the armature to accommodate the other brush and the switch device which is operable by the thumb of the hand grasping the drill to start and stop the motor.

20 The general purpose and object of my invention is to provide an improved switch device having its insulating casing composed of a pair of separable overlapping sections and secured together in assembled relation by a single fastening element 25 to simplify the switch construction and reduce its cost of manufacture.

20 A further object of my invention is to provide the switch casing sections with interfitting parts, preferably about the fastening element, to hold the sections against displacement in the plane 30 of their meeting edges.

35 A further object of my invention is to make the switch casing sections substantially alike to reduce manufacturing costs and to facilitate assembling the construction.

Other and further objects of my invention will appear from the following specification, taken in connection with the accompanying drawing, in which:—

40 Fig. 1 is a side view of a small portable electric hand drill provided with a switch device of my invention, the outer casing of the drill and associated member of the handle being broken away and in section, respectively, to show the switch 45 device;

Fig. 2 is a horizontal sectional view taken through the drill at the switch device on line 2—2 of Fig. 1;

Fig. 3 is a perspective view of the two sections 50 of the switch casing in disassembled relation; and

Fig. 4 is an enlarged elevational view, partly in section, to show one of the contact members on the outer side of the switch casing.

In the drawing, 1 indicates the outer casing 55 of the drill enclosing the electric motor which

furnishes the power for rotating the chuck shaft or spindle 2. The motor, as shown, is of the horseshoe type having its armature 3 in the lower portion of the casing 1 and its field coil 4 in the upper portion of said casing.

The single handle 5 of the drill is of the pistol grip type. The handle is at the rear end of the casing 1 and extends outwardly therefrom in transverse relation to the axis of the armature 3. The handle 5 is hollow and comprises a forward 10 member 6 preferably cast integral with the casing 1. The rear part 7 of the handle is removable providing a cover on the rear side of the handle for the compartment 8 which the handle forms with the casing 1.

The hollow handle 5 provides a duct for the intake of cooling air for the motor and is provided at its outer or lower end with an opening 9. This opening allows for the intake of the cooling air and also accommodates a cable 10 containing the current supply wires 11, 12 for the tool. One part of the opening 9 is in the forward part 6 of the handle and the remaining part is in the removable cover section 7, thus enabling the opening to be split on removing the 25 cover section.

The armature shaft 13 of the motor is journaled in ball bearings 14, 14a, one in the gear housing 15 at the front end of the drill, and the other in the casing 1 at the handle 5. At this 30 location, the casing 1 supports a cup 16 in which the bearing 14a is mounted as shown in Fig. 1. The cup 16 is preferably made integral with the casing 1 and also receives a screw 17 for removably securing the rear part 7 of the handle 5 in place.

The gear housing 15 also contains the bearings 18, 18a for the chuck shaft 2 and the driving connection from the armature shaft 13 to the chuck shaft 2. This driving connection comprises a gear 40 19 fixed to the chuck shaft and in constant mesh with a pinion 20 provided on the armature shaft 13. The chuck shaft 2 is offset laterally from the armature shaft 13 and is disposed on the side of the armature shaft opposite the handle 5.

A rotary fan 21 is fixed to the armature shaft 13 in the forward part of the casing 1 just rearward of gear housing 15. The fan member 21 is rotated by the motor and draws cooling air over the motor through the air duct provided by the 50 hollow handle 5. The fan 21 discharges the air out of the casing 1 through a number of holes 22 in the casing at the periphery of the fan and in tangential relation thereto as in the Forss Patent No. 1,652,401, granted December 13, 1927.

Associated with the commutator 23 of the motor are two brushes 24, 25 each mounted in a brush holder respectively arranged above and below the axis of the motor as shown. The lower holder 26 is located in the handle part 6 and is electrically connected with the supply wire 11 through a connector 27. The latter has a contact 28 to which the supply wire is attached and said contact engages the metal conducting sleeve 29 in which the brush 25 is slidably mounted and normally urged against the commutator by a spring (not shown) located in said sleeve. The connector construction constitutes the subject matter of the Herman Kuehne application, Serial No. 15 45,545, filed October 18, 1935.

The upper brush 24 is directly above the lower brush and is slidably mounted in a metal sleeve 30 in the holder case 31, which like the lower case 26 is made of suitable electrical insulating material. The upper brush holder 31 is removably mounted in the rear part of the casing 1 adjacent the cover plate 7 of the handle 5 in a channel shaped support 31a preferably made integral with the tool casing 1 as shown in Figs. 1 and 2. The 20 metal sleeve 30 is exposed on its side facing the coil 4 of the motor. The upper brush 24 is also slidably mounted in its metal sleeve 30, and like the lower brush is normally urged against the commutator 23 by a spring 32, as shown in Fig. 1. The outer or upper end of the sleeve 30 is closed by a plug 33 of insulating material screwed into the casing 1 to removably secure the upper brush holder in said casing. A similar plug 34 closes the outer or lower end of the sleeve 29 and this 35 plug removably secures the lower brush holder in the handle 5.

The switch device for the tool is located in the casing 1 in the space between the upper brush holder support 31a and the coil 4 of the motor as shown. The switch assembly comprises a casing 40 comprised of two substantially similar, separable sections 35, 36, each made of an electrical insulating material, preferably light in weight and which can be die cast. The sections 35, 36 are chambered as at 37 to provide a compartment for accommodating the active or movable parts of the switch mechanism when the sections are in assembled relation with their chambers in communication. The movable contact of the switch device comprises a substantially U-shaped element 38, the arms of which are respectively fulcrumed between two sets of lugs 39, 39, one set in each chamber 37 as shown in Fig. 3. The yoke portion of this switch member is connected by a coil spring 38a with an actuating button 40 slidably mounted at one end of the switch casing as shown in Fig. 2. This button has a shank piece (not shown) extending into the compartment formed by the chambers 37 through a slot 41 provided along the 55 joint between the sections 35, 36, the portions 41a, 41b of the slot being in the respective sections as shown in Fig. 3.

The switch device is located in the casing 1 in transverse relation to the upper brush holder and has an interlocking connection with said holder for holding the switch device in the tool casing. This connection is formed by providing the switch case sections with outwardly opening side channels 42, 43, the former of which receives the upper brush holder casing 31 as shown in Fig. 2. The tool casing 1 has aligned openings 44, 45 in its side walls to receive and support the switch casing as shown. These openings conform to the shape of the switch casing which is rectangular 75 as shown. The switch device as a unit is slid end-

wise into the casing through one opening, whereupon the upper brush holder is slid into place and interlocks with the switch device to hold it in place. The button 40 being at one end of the switch device is positioned at one side of the tool 5 and within convenient reach of the thumb of the hand grasping the handle. The button is movable to the opposite ends of the slot 41, and when at one end of the slot opens the circuit to the motor, whereas when at the opposite end of the 10 slot closes the circuit. The lugs 46, 47 in the casting sections 35, 36 provide stops for the switch yoke 38.

In accordance with my invention, the casings 35, 36 are secured together in assembled relation by a single fastening member 48 which as shown in Fig. 2 passes through both sections in their overlapping portions exterior of the chambers 37. The fastening member is preferably in the form of a bolt having its head 49 20 and its clamping nut 50 countersunk in recesses provided in the respective sections. The latter have registering openings 51, 51 for the bolt and these openings continue through dowels 52, 52, one on the inner side of each section 35, 36. 25 Each dowel projects outwardly to substantially the same extent from the inner surface of its associated section, and fits in a recess 53 in the opposite section when the sections are in assembled relation. The dowels and the recesses 30 are non-circular in form and when interfitting prevent displacement of the casing sections 35, 36 about the axis of the bolt 48 or in the plane of the meeting edges of the sections. Thus, the latter are secured together by a single fastening element instead of by a number of elements as heretofore. This adds to the simplicity and the low cost of the switch construction and facilitates its assembly. The dowels 52 completely surround the bolt 48 when the parts are 40 assembled, this being brought about by having a portion of each bolt hole in the associated dowel, as shown in Fig. 3.

The fixed contacts 54, 55 for the switch device are carried by its respective casing sections 35, 36 in channels 42, 43 therein as shown in Fig. 2. These contacts are similar in form and each comprises a metal plate 56 which has integral tangs 57, 57 at one end fitting in grooves 58, 58 in the side walls of the associated channel, as shown 50 in Fig. 4. The tangs are co-planar with the plate and slide into the grooves on inserting the plate endwise into the channel. The plate, being of sheet metal, is resilient and carries a contact lug 59 at its end opposite the tangs. This 55 lug snaps into an opening 60 in the associated casing section, and is exposed in the chamber 37 for engagement by the yoke piece 38 of the switch mechanism when the yoke is in "on" position.

Each plate 56 is provided with a struck out portion providing a spring tongue 61. The tongue of the plate on the side of the switch casing adjacent the coil 4 of the motor contacts with a contact strip or bar 62 of the coil and 65 in the electrical connection at one end with the coil winding 63 as at 64 in Fig. 2. The tongue 61 of the other plate contacts the exposed side of the metal sleeve 30 of the upper brush holder 31, as shown in Figs. 1 and 2. 70 Thus, the tongues 61 connect the switch device in the motor circuit and enable the switch device to control the supply of current to the tool.

The contact strip 62 is supported by the insulating bobbin 63a of the coil winding and 75

extends in the direction of endwise movement of the switch device into and out of the casing 1 as shown in Fig. 2. Thus, the switch device is connected in the motor circuit on sliding the switch device into the casing. The wire 12 is connected to a stator wire 12a at a binding post 12b at the connector 27. The stator 65 extends through the bobbin 63a and down on opposite sides of the armature 3, as in a horseshoe motor construction. The stator wire is connected to the coil winding 63. The motor circuit includes this winding, switch device, brushes, commutator, and the wires referred to. The switch casing is preferably divided longitudinally, that is, in the direction in which it is inserted into the casing 1. The intake for the cooling air may be augmented by openings along the meeting edges of the handle sections 6, 7 as in the upper portions, as at 68, in Fig. 1. The feature of the contact strip 62 in association with the switch device and the bobbin 63a and the construction of the bobbin constitute the subject matter of the co-pending Frithiof P. Forss application, Serial No. 45,541, filed October 18, 1935.

The gear housing 15 is provided with a cover plate 66 on its rear side to divide the gear housing from the casing 1. This plate constitutes a part of the gear housing assembly, which is removably secured to the casing 1 by fastening screws 67. The cable 10 is fastened to the handle section 6 by a clamping strip 68.

The channel 42 is deep enough to receive the brush holder case 31 so as to interlock the switch device with said holder. The channel 43 is shallower so that the tongue of the contact plate in said channel may extend out of the same to engage the bar 62 on sliding the switch device into the casing 1. The channel 43 is made shallow by facing off the body of the casing section 36 after the same is made. Otherwise, the casing sections are alike, both being duplicates when produced. This contributes to the simplicity of the construction, and as before stated, reduces manufacturing costs.

In this connection with making the sections 35, 36 duplicates, it is pointed out that the casing sections 35, 36 are made with the dowels 52, 52 on the same side of the bolt holes 51 and 50 with the recesses 53, 53 for the dowels on the opposite side of said holes. Thus when the sections are assembled from the positions shown in Fig. 3, the dowel on one section will enter the recess on the other section. Two openings 60 are made in each section 35, 36, one adjacent one side edge of the section, and the other opening adjacent the opposite side of the section. This enables the contacts 59 for the switch piece 38 to be in opposition when the contact plates 54, 55 are fitted in the channels 42, 43 from the same ends of said channels. Each channel has a set of grooves 58 at its opposite ends so that the contacts 59 may be reversed from the positions shown whenever desired. The extra set of grooves in the channel 43 are indicated in dotted lines 58a, 58a in Fig. 4.

The drill shown has a free speed of approximately 2500 R. P. M. and operates on the usual commercial electric current of 110 volts. The motor is of the universal type, operating on either a D. C. or an A. C. current. The drill is relatively small and light in weight. It is held in one hand, and being small may be used in close quarters to drill at any desired angle.

The details of construction and arrangement

of parts shown and described may be variously changed and modified without departing from the spirit and scope of my invention, except as pointed out in the annexed claims.

I claim as my invention:

1. In a hand drill of the character described, an outer casing, an electric motor of the horseshoe type located in said casing and arranged with its armature in the lower portion of the casing and its field coil in the upper portion of the casing, a hollow handle at the rear end of the casing, upper and lower brush holders and brushes therein for the motor, the lower brush holder being located in the handle and the upper brush holder being located in the casing above the handle and in spaced relation to the field coil, a support in the casing for the upper brush holder, said coil having an electrical contact surface facing said support, and a manually operable switch device for the motor, said switch device being removably mounted in the casing between the upper brush holder support and the field coil and having yieldable contacts on its opposite sides to respectively engage the upper brush holder and the field coil contact surface when the switch device is in operative position in the casing.

2. In a hand drill of the character described, an outer casing, an electric motor of the horseshoe type located in said casing and arranged with its armature in the lower portion of the casing, and its field coil in the upper portion of the casing, a hollow handle at the rear end of the casing, upper and lower brush holders and brushes therein for the motor, the lower brush holder being located in the handle and the upper brush holder being located in the casing above the handle and in spaced relation to the field coil, a support in the casing for the upper brush holder, said coil having an electrical contact surface facing said support, and a manually operable switch device for the motor, said switch device being removably mounted in the casing between the upper brush holder support and the field coil and having contacts on its opposite sides for electrical connection with the upper brush holder and the field coil contact surface, respectively, said switch device having a casing composed of a pair of substantially similar sections, each provided with one of the switch contacts.

3. In a hand drill of the character described, an outer casing, an electric motor of the horseshoe type located in said casing and arranged with its armature in the lower portion of the casing and its field coil in the upper portion of the casing, a hollow handle at the rear end of the casing, upper and lower brush holders and brushes therein for the motor, the lower brush holder being located in the handle and the upper brush holder being located in the casing above the handle and in spaced relation to the field coil, a support in the casing for the upper brush holder, said coil having an electrical contact surface facing said support, and a manually operable switch device for the motor, said switch device being removably mounted in the casing between the upper brush holder support and the field coil and having yieldable contacts for connecting the switch device with the upper brush holder and the field coil contact surface, respectively, when the switch device is in operative position in the casing, said switch device having channels in its opposite sides for the respective switch contacts, one channel being deep enough to have the upper brush holder interfit therewith, and the other channel being shallower so that the switch contact in said chan-

nel may project beyond the same to engage the field coil contact surface.

4. In a hand drill of the character described, an outer casing, an electric motor of the horseshoe type located in said casing and arranged with its armature in the lower portion of the casing and its field coil in the upper portion of the casing, a hollow handle at the rear end of the casing, upper and lower brush holder and brushes there-
5 in for the motor, the lower brush holder being located in the handle and the upper brush holder being located in the casing above the handle and in spaced relation to the field coil, a support in the casing for the upper brush holder, said field
10 coil having an electrical contact surface facing said support, and a manually operable switch device for the motor, said switch device being removably mounted in the casing between the upper brush holder support and the field coil and having yieldable contacts on its opposite sides to respectively engage the upper brush holder and the field coil contact surface when the switch device is in operative position in the casing, said switch device having a casing composed of a pair
15 of separable overlapping sections, and a single fastening element for securing the sections in assembled relation.
5. In a hand tool of the character described, an outer casing having side walls, an electric motor
20 in said casing, spaced contact elements in the casing for the motor circuit, supports in the casing for said elements, said casing having aligned openings in its side walls between said supports, and a manually operable switch device insertable
25 in the casing through said openings and having resilient contact members on its opposite sides to engage said contact elements, said switch device having an outer casing consisting of separable sections, a switch operating mechanism located
30 between said sections and having an operating button at one end of the sections, and means for securing the switch casing sections together, said means being located adjacent the end of the sections opposite the button, said securing means comprising interfitting dowels and recesses on the respective sections, and a single fastening element extending through the switch casing sections at the dowels and recesses, respectively, and
35 confined between the outer sides of the sections.

vice having an outer casing consisting of separable sections, a switch operating mechanism located between said sections and having an operating button at one end of the sections, and means for securing the switch casing sections together, said means being located adjacent the end of the sections opposite the button, said securing means comprising interfitting parts on the inner sides of the switch casing sections and a single fastening element extending through the 10 switch casing sections at the interfitting parts and confined between the outer sides of the sections.

6. In a hand tool of the character described, an outer casing having side walls, an electric motor 15 in said casing, spaced contact elements in the casing for the motor circuit, supports in the casing for said elements, said casing having aligned openings in its side walls between said supports, and a manually operable switch device insertable 20 in the casing through said openings and having resilient contact members on its opposite sides to engage said contact elements, said switch device having an outer casing consisting of separable sections, a switch operating mechanism located 25 between said sections and having an operating button at one end of the sections, and means for securing the switch casing sections together, said means being located adjacent the end of the sections opposite the button, said securing means 30 comprising interfitting dowels and recesses on the respective sections, and a single fastening element extending through the switch casing sections at the dowels and recesses, respectively, and
35 confined between the outer sides of the sections.

FRANK B. HAMERLY.
